Notice of Allowance dated Apr. 18, 2016 from U.S. Appl. No. 29/527,085.

Office Action dated Feb. 1, 2016 from U.S. Appl. No. 29/516,707.

Primary Examiner — Rhea Shields(74) *Attorney, Agent, or Firm* — Ward and Smith, P.A.;
 Ryan K. Simmons(57) **CLAIM**

The ornamental design for a closeable container, as shown and described.

DESCRIPTION

FIG. 1 is a perspective view of a closeable container showing a new design;

FIG. 2 is a front elevation view thereof, the rear being a mirror image;

FIG. 3 is a top plan view thereof;

FIG. 4 is a bottom plan view thereof; and,

FIG. 5 is another perspective view thereof, showing the closeable container in an open configuration.

In FIGS. 1-5 the dash-dash dotted lines are for the purpose of illustrating perforations and form part of the claimed design.
